AERIAL TOY

Filed April 13, 1932

UNITED STATES PATENT OFFICE

WALTER A. MARTIN, OF LA CRESCENTA, CALIFORNIA

AERIAL TOY

Application filed April 13, 1932. Serial No. 605,077.

This invention relates to and has for a purpose the provision of a simple and inexpensive toy which in one of its many aspects simulates an airplane of the heavier-than-air type intended to be attached to a moving element, such as an automobile, and which in its application to the radiator cap of the vehicle provides an attractive ornament therefore, and responds to forward motion of the vehicle, by rising to and maintaining a flying position under the action of the air currents thus induced.

It is a further purpose of the invention to provide an aerial toy in which the airplane or other object which is simulated is mounted on a horizontal axis for movement throughout a complete circular path, the plane of which is parallel to the direction of forward motion of the vehicle to which the toy is attached, to the end that when the vehicle is at rest, the airplane will be suspended in an inverted position under the action of gravity and will swing upwardly to an upright flying position in response to the action of the air currents against lifting surfaces of the airplane, induced by the motion of the vehicle.

One form of the invention will now be described, and the novel features thereof then pointed out in claims.

In the accompanying drawing,

Figure 1 is a view showing in side elevation the aerial toy attached to the radiator cap of an automobile, and illustrating the position that the toy occupies when the automobile is at rest;

Figure 2 is a view similar to Figure 1, but illustrating the position occupied by the toy when the vehicle is in forward motion;

Figure 3 is a view of the toy in front elevation;

Figure 4 is a horizontal sectional view taken on the line 4-4 of Figure 1 and looking in the direction of the arrows.

Referring specifically to the drawing, wherein corresponding reference characters designate the same parts in each of the several views, this invention in its present embodiment comprises a support or bracket S constructed of relatively heavy wire to pro-

vide an attaching portion 10 and a portion 11 at right angles thereto which constitutes a mounting for the toy object, in the present instance in the form of a miniature airplane A.

The portion 10 is constructed to provide two arcuate clamping members 12 and 13, one of which is separable from the other and is detachably connected thereto at diametrically opposed points by bolts 14 passing through eyes 15 formed on the members. Nuts 16 are threaded on the bolts 14 for action therewith in clamping the support to the filling spout 17 of an automobile radiator 18 immediately beneath the cap 19 of the radiator, so as to leave the cap free to be applied and removed from the spout as desired.

With the support thus applied, its portion 11 occupies an upright position, and it is to be noted that the portion 11 is laterally offset as indicated at 20, in a direction transversely of the automobile to which the support is attached. The lateral offset is substantially C-shaped as viewed in the front elevation of Figure 3, and terminates at its upper end in a horizontally disposed pivot pin 21, the longitudinal axis of which extends transversely of the length of the automobile.

The pin 21 provides a pivotal mounting for the miniature airplane A or other object, and to this end, a rigid member or arm 22 in the form of a length of stiff wire is coiled at one end to form a sleeve 23 freely receiving the pin, which latter has its free end bent laterally to prevent axial displacement of the sleeve from the pin. The opposite end of the arm 22 is rigidly secured by staples 24 to the fuselage 25 of the airplane, and it is to be noted that the lateral offset 20 of the portion 11 of the support S is sufficient to enable the wings 26 of the airplane to clear the portion 11, and thus render the airplane free to travel a complete revolution about the axis of the pin 21. As this path of movement is parallel to the direction of forward motion of the automobile, the airplane will be acted upon by the air currents induced by such motion of the automobile.

The operation of the invention is as follows:

When the aerial toy is applied to an automobile as above described, the airplane A 5 will be suspended from the pin 21 by the arm 22, to occupy an inverted position under the action of gravity when the automobile is at rest, which position is shown in Figure 1 and in broken lines in Figure 3.

10 However, when the automobile is traveling forward in the direction of the arrow in Figure 2, the air currents thus induced will act upon the wings 26 to swing the airplane upwardly to and maintain it in the flying position shown in this figure and in full lines in Figure 3. The airplane will thus be maintained in a level position by the induced air currents, and will be confined by the rigid arms 22 and pin 21, to travel in a circular 15 path from the inverted position to flying position in response to forward motion of the vehicle. When movement of the vehicle ceases, the airplane will gravitate to inverted position, wherein it will remain until forward motion of the vehicle is again initiated.

20

25

What is claimed is:

1. An aerial toy comprising: a support adapted to be secured to a vehicle; a toy object; and means for mounting said object on 30 the support for rotary movement in a complete circular path about a horizontal axis extending transversely of the direction of

the vehicle's forward motion, so that the object will be suspended in an inverted position below said axis when the vehicle is at rest; the object having a lifting surface responsive to air currents induced by forward motion of the vehicle, to swing the object from said inverted position upwardly to a flying position above said axis.

2. An aerial toy comprising: a toy object having wings; a support; a rigid arm secured to said object and rotatably mounted on the support about a fixed axis; and means for securing the support on a vehicle; the support having a lateral offset therein to enable said object to travel in a complete circular path and to occupy an inverted position below said axis when the vehicle is at rest, for movement of the object to a flying position above said axis by the action of induced air currents against the wings of the object when the vehicle is in motion.

3. An aerial toy comprising: a toy object; a support; means for mounting said object on the support for rotational movement in a complete circular path; means for securing the support to a vehicle to suspend the object in a lowered position when the vehicle is at rest; and means responsive to the action of air currents induced by motion of the vehicle, to move the object to a raised position.
